ABSTRACT OF THE DISCLOSURE

A washing powder containing a 3:1 to 1:3, by weight, mixture of soap and non-soap detergent is obtained with surprisingly good and stable lather if the non-soap detergent is a water-soluble C_{10} to C_{20} substantially straight-chain aliphatic alpha-sulphonate and if there is included in the composition from 1½% to 6%, by weight of the powder, of an unsubstituted amide of a C_{10} to C_{16} substantially straight-chain aliphatic acid or, when the alpha-sulphonate is an alkane sulphonate, the unsubstituted amide or a monoethanolamide of the C_{10} to C_{16} substantially straight-chain aliphatic acid.

This invention relates to washing powders. In particular it relates to a washing powder containing soap and non-soap detergent in which the weight ratio of soap to non-soap detergent is between 3:1 and 1:3.

A washing powder containing such a blend of soap and non-soap detergent possesses to some extent the good features of both a non-soap detergent powder and a soap powder. Thus, like a non-soap detergent powder, it gives quick lather and little trouble with washing-machine heaters and, like a soap powder, it gives close, creamy lather and easy rinsing. Unfortunately, in general, the lather formed from such a blend, although it is creamy and quickly formed, has a short half-life even when a lather stabilizer is added to the powder.

It has been discovered that a washing powder of the above type has surprisingly good and stable lather when the powder contains soap, a C_8 to C_{22} substantially straight-chain aliphatic alpha-sulphonate and, by weight of the powder, from 1½% to 6%, preferably 3%, of an unsubstituted amide of a C_{10} to C_{16} fatty acid.

The invention provides a washing powder containing soap and a C_8 to C_{22} substantially straight-chain aliphatic alpha-sulphonate, in a weight ratio of 3:1 to 1:3, and, by weight of the powder, between 1½% and 6% of an unsubstituted amide of a C_{10} to C_{16} substantially straight-chain aliphatic acid.

PKA and CNA are typical examples of unsubstituted amides of C_{10} to C_{16} fatty acids. PKA is the mixture of amides derived from palm kernel oil and CNA the mixture of amides derived from coconut oil.

A preferred alpha-sulphonate is an alkene sulphonate.

A particularly preferred alpha-sulphonate is obtained when the sulphonation mixture obtained by sulphonating C_{11} to C_{22} alpha-olefins is completely or almost completely hydrolysed and neutralised. Preferred sulphonating agents are sulphur trioxide/air or sulphur trioxide adducts such as sulphur trioxide-dioxane. The full constitution of the sulphonation mixture is not known but it is believed to contain beta-, gamma- and delta-sultones as well as alkene sulphonates and hydroxysulphonates. The sulphonation mixture is preferably hydrolysed and neutralised with sodium hydroxide solution to give the sodium sulphonates but water-soluble salts with other cations, such as ammonium, substituted ammonium and potassium can be used.

2

The product obtained by hydrolysing and neutralising the sulphonation mixture obtained by sulphonating alpha-olefins, herein called an alpha-olefin sulphonate, contains hydroxyalkane sulphonates, disulphonates and other compounds as well as alkene sulphonates. A typical product consists essentially of from 40% to 80% of alkene sulphonates, the double bond being predominantly in the 2,3; 3,4; and 4,5 positions, 15% to 40% of hydroxy alkane sulphonates and from 3% to 25% of disulphonates. All these compounds have an alpha-sulphonate group present in their structure.

Another preferred alpha-sulphonate is an alkane sulphonate of the general formula RSO_3X where R is a primary, straight chain, C_{11} to C_{22} , saturated alkyl group and X is a cation such as an ammonium, sodium or potassium ion.

When the alpha-sulphonate is an alkane sulphonate a monoethanolamide of a C_{10} to C_{16} fatty acid can be used instead of an unsubstituted amide as lather stabiliser.

It has been discovered that a washing powder with especially good lather characteristics is formed when the powder contains the alphasulphonate and soap in a weight ratio of 1:1. It will be appreciated that, according to the invention, minor proportions of other non-soap detergents can be included in the powder.

The total amount of soap and alpha-sulphonate will be between 10 and 40%, by weight of the powder.

By water-soluble is meant that the salt of the C_8 to C_{22} substantially straight-chain aliphatic acid and the salt of the alpha-sulphonate are, at the usual user concentration of a washing powder, substantially soluble in the washing solution. The usual user concentration of a washing powder is about 0.4% by weight.

The invention is particularly applicable to built detergent compositions. In such compositions the amount of detergent active, soap and non-soap detergent, will normally be between 10 and 40% and the amount of builder salt, such as sodium tripolyphosphate, will normally be between 20 and 50% by weight of the composition.

By soap is meant a water-soluble salt of a C_8 to C_{22} substantially straight-chain aliphatic acid. The salt may be an alkali-metal, ammonium or substituted ammonium salt.

Many housewives believe that when the lather subsides the detergent solution has lost its washing power. Consequently they often overdose and waste detergent. The compositions according to the invention, as is shown in the following examples, have long half-lives compared to other soap/non-soap detergent compositions. There is therefore a reduced tendency for overdosing and consequent waste to occur.

EXAMPLE I

This example illustrates the superior lathering performance of the compositions of the invention in comparison with other soap/non-soap detergent based washing powders.

A number of drum dried washing powders containing soap and a non-soap detergent were prepared with and without a lather stabilizer. These powders were screened for lather stability in hard water. 0.4% of each powder

was stirred at 75 r.p.m. into 24° H. water at 60° C. After $\frac{1}{2}$ minute the stirrers were stopped and the lather height measured in $\frac{1}{10}$ ins. initially and after $\frac{1}{2}$, 1, 2, 3, 4 and 5 mins. The half-lives in minutes of the lather produced are given in Table I and Table II below.

The composition of the powder base used in Table I was:

	Parts
Soap	10
Non-soap detergent	10
Sodium tripolyphosphate	32
Sodium sulphate	11
Sodium toluene sulphonate	2
Anhydrous alkaline silicate	10
Sodium carboxymethyl cellulose	1
Water	10

The soap used in the formulations was a commercial soap made from a mixture of tallow, nut and soft oils and contained approximately:

23% of $< C_{15}$ saturated soaps

35% of $\geq C_{15}$ saturated soaps

42% of unsaturated soaps

The lather stabilizers employed were CEA, PKA, CNA, and LDAO. LDAO is lauryl dimethylamine oxide, CEA 25 is the monoethanolamide of the acids derived from coconut oil.

5 Powders were prepared according to the formulation given in Example I. Powder equivalent to 0.4% concentration was added to 24° H. water (24 parts CaCO_3 per 100,000 parts water) as 60° C. in a paddle-type washing machine. The solution was agitated for 30 seconds and the lather height noted. The solution was then agitated for a further 30 seconds and the height noted. The solution was finally agitated for a further minute and the final height noted. The results are given in Table III.

EXAMPLE III

10 Powders were prepared according to the formulation given in Example I. Powder equivalent to 0.4% concentration was added to 24° H. water (24 parts CaCO_3 per 100,000 parts water) as 60° C. in a paddle-type washing machine. The solution was agitated for 30 seconds and the lather height noted. The solution was then agitated for a further 30 seconds and the height noted. The solution was finally agitated for a further minute and the final height noted. The results are given in Table III.

TABLE III

		Lather booster, 3%	Lather heights in inches at times			
			0	$\frac{1}{2}$	1	2 mins.
15	Non-soap detergent

20 What is claimed is:

1. A washing powder consisting essentially, by weight of the powder, of:

- (a) a soap being an alkali metal or ammonium water-soluble salt of a mixture substantially straight-chain unsubstituted aliphatic C_8 – C_{22} carboxylic acid;
- (b) a non-soap detergent being an alkali metal or am-

TABLE I

Non-soap Detergent	Half-lives of lather (in mins.)		
	No lather stabilizer	3% CEA	3% PKA
Na-Alkyl benzene sulphonates from:			
Commercial linear alkyl benzene with a mean molecular weight of 256 (broad distribution of side chain length)	$\frac{1}{2}$	Less than $\frac{1}{2}$	
Commercial linear alkyl benzene with a mean molecular weight of 238 (narrow distribution of side chain length)	do	do	Less than $\frac{1}{2}$
Commercial linear alkyl benzene with a mean molecular weight of 257 (narrow distribution of side chain length)	do	do	No lather.
Na-Tallow alcohol sulphate	Less than $\frac{1}{2}$	$\frac{1}{2}$	do
Na- C_{11} – C_{14} synthetic primary alcohol sulphate	$1\frac{1}{2}$	Less than $\frac{1}{2}$	$\frac{1}{2}$
Sulphate from "random" $1\frac{1}{2}$ C_{11} – C_{14} synthetic alcohol-Na salt	No lather	$\frac{1}{2}$	do
Sulphate from "random" $1\frac{1}{2}$ C_{11} – C_{14} synthetic alcohol-Na salt	do	1	$\frac{1}{2}$
Sulphate from "random" $1\frac{1}{2}$ C_{11} – C_{14} synthetic alcohol-Na salt	do	1	$\frac{1}{2}$
Na-Tallow ether sulphate (4 moles ethylene oxide)	$\frac{1}{2}$	Less than $\frac{1}{2}$	Less than $\frac{1}{2}$
Na-Lauryl ether sulphate (5 moles ethylene oxide)	No lather	1	do
Na-Lauryl ether sulphate (10 moles ethylene oxide)	do	$\frac{1}{2}$	$\frac{1}{2}$
Na-secondary (C_{11} – C_{14}) ether sulphate (3 moles ethylene oxide)	$1\frac{1}{2}$	$\frac{1}{2}$	do
Na- $"random"$ $1\frac{1}{2}$ C_{11} – C_{21} alkane sulphonate	No lather	1	do
Coconut fatty acid ester of sodium isethionate	do	1	do
Sodium salt of lauroyl-N-methyl taurine	do	1	1
Na-dodecyl β -alanine	$\frac{1}{2}$	1	1
Na- C_{11} – C_{20} alkane alpha-sulphonate	do	5	5
Na- C_{11} – C_{14} alpha-olefin sulphonate	Less than $\frac{1}{2}$	1	4

¹ The term random means that the functional group is randomly distributed over all the positions in the hydrocarbon chain.

EXAMPLE II

The composition of the powder base used in Table II was:

	Parts
Soap	10
Non-soap detergent	10
Sodium tripolyphosphate	32
Sodium sulphate	11
Anhydrous alkaline silicate	10
Sodium toluene sulphonate	2
Sodium carboxymethyl cellulose	1
Water	11
PKA or CEA	3

The powders were tested as described in Example I.

TABLE II

Non-soap Detergent	(Half-lives of lather in mins.)		
	No lather stabilizer	With 3% PKA	With 3% CEA
Na dodecyl-1-sulphonate	0	5	$2\frac{1}{2}$
Na tetradecyl-1-sulphonate	0	$2\frac{1}{2}$	$3\frac{1}{2}$
Na octadecyl-1-sulphonate	0	5	$3\frac{1}{2}$
Na- C_{11} – C_{14} -1-sulphonate	$1\frac{1}{2}$	5	$3\frac{1}{2}$
Na- C_{11} – C_{20} -1-sulphonate	$1\frac{1}{2}$	5	4

monium water-soluble salt of a substantially straight-chain aliphatic C_{10} – C_{20} alpha sulphonic acid;

(c) said substantially straight-chain aliphatic C_{10} – C_{20} alpha sulphonic acid being an unsubstituted alkane sulphonic acid or a mixture of unsubstituted alkene sulphonic acid, hydroxy alkane sulphonic acid and di-sulphonic acid;

(d) the weight ratio of soap to non-soap detergent being from 1:3 to 3:1 and

(e) from 1:2 to 6% of an unsubstituted amide of a substantially straight-chain unsubstituted aliphatic C_{10} – C_{16} carboxylic acid when said alpha sulphonic acid is an alkene sulphonic acid, and when said alpha sulphonic acid is an alkane sulphonic acid 1:2% to 6% of an unsubstituted amide of a substantially straight-chain aliphatic C_{10} to C_{18} fatty acid.

2. A washing powder according to claim 1, in which the substantially straight-chain aliphatic C_{10} – C_{20} alpha sulphonic acid is a mixture of, by weight of the said alpha sulphonic acid, from 40% to 80% of alkene sulphonic acid, from 15% to 40% of hydroxy alkane sulphonic acid and from 3% to 25% of di-sulphonic acid.

3. A washing powder consisting essentially, by weight of the powder, of:

(a) from 5% to 20% of an alkali metal or ammonium

(b) from 1:2 to 6% of an unsubstituted amide of a substantially straight-chain unsubstituted aliphatic C_{10} – C_{16} carboxylic acid when said alpha sulphonic acid is an alkene sulphonic acid, and when said alpha sulphonic acid is an alkane sulphonic acid 1:2% to 6% of an unsubstituted amide of a substantially straight-chain aliphatic C_{10} to C_{18} fatty acid.

water-soluble salt of a mixture substantially straight-chain unsubstituted aliphatic C₈—C₂₂ carboxylic acid; (b) from 5% to 20% of an alkali metal or ammonium water-soluble salt of a substantially straight-chain aliphatic C₁₀—C₂₀ alpha sulphonic acid consisting essentially of, by weight of the said alpha sulphonic acid, from 40% to 80% of alkene sulphonic acid, from 15% to 40% of hydroxy alkane sulphonic acid and from 3% to 25% of di-sulphonic acid;

- (c) from 20% to 50% of an inorganic builder salt; (d) from 1½ to 6% of an unsubstituted amide of a substantially straight-chain aliphatic C₁₀—C₁₆ carboxylic acid; (e) about 12% of anhydrous alkaline silicate;

the weight ratio of water-soluble carboxylic acid salt to the water-soluble alpha sulphonic acid salt being about 1:1.

4. A washing powder consisting essentially by weight of the powder, of:

- (a) from 5—20% of an alkali metal or ammonium water-soluble salt of a mixture substantially straight-chain unsubstituted aliphatic C₈—C₂₂ carboxylic acid; (b) from 5—20% of an alkali metal or ammonium wa-

10
